Josiah Comly's Design for combined Top Plate and
Combustion and Air Chamber, & a Vapor Generator

4346

and Burner

PATENTED SEP 13 1870

United States Patent Office.

JOSHUA COMLY, OF PHILADELPHIA, PENNSYLVANIA.

Design No. 4,346, dated September 13, 1870.

DESIGN FOR COMBINED TOP PLATE, COMBUSTION, AND AIR-CHAMBER OF A VAPOR-GENERATOR AND BURNER.

The Schedule referred to in these Letters Patent and making part of the same.

I, JOSHUA COMLY, of the city of Philadelphia and State of Pennsylvania, have invented and produced a new and original Design for Combined Top Plate and Combustion and Air-Chamber of a Vapor-Generator and Burner.

The nature of my design is fully represented in the accompanying photographic illustration, to which reference is made.

A is the top plate;

B, the combustion-chamber; and

C, the air-chamber.

The air-chamber has openings *a* all around, for the

passage of air, and the combustion-chamber register-openings *a'*.

I claim as my invention—

A design for combined top plate and combustion and air-chambers, for vapor-generators and burners, as described and shown.

In testimony that the above is my invention or discovery, I have hereunto set my hand and affixed my seal this 11th day of March, 1870.

Witnesses: JOSHUA COMLY. [L. s.]
THOMAS J. BEWLEY,
STEPHEN USTICK.
